UNITED STATES PATENT OFFICE.

WILLIAM JOHN VINCENT, OF CARDIFF, WALES.

ROTARY HYDRAULIC APPARATUS.

1,268,515.

Specification of Letters Patent. Patented June 4, 1918.

Application filed August 14, 1914. Serial No. 856,844.

To all whom it may concern:

Be it known that I, WILLIAM JOHN VINCENT, a subject of the King of Great Britain, and a resident of Cardiff, Wales, have invented certain new and useful Improvements in Rotary Hydraulic Apparatus, of which the following is a specification.

This invention relates to improvements in rotary hydraulic apparatus and has reference to that type of apparatus consisting of pumps and motors wherein a variable delivery pump driven at constant speed by a prime mover transmits liquid under pressure to a hydraulic motor connected to drive the member or machine to which it is desired to transmit motion and the speed of the driven member is regulated and controlled by varying and controlling the stroke or delivery of the pump.

The present invention consists of a particular construction of pump and arrangements whereby such pump is combined with a motor for purposes of a hydraulic transmission gear.

In order that my invention may be more readily understood and carried into practice, reference is hereby made to the accompanying illustrative drawings wherein:

Figure 1 is a sectional elevation of a transmission device constructed in accordance with my invention.

Fig. 2 is a partial sectional plan of the casing with the rotor and its parts removed.

Fig. 3 is a sectional view of the casing on line 1—1 of Fig. 1 looking in the direction of the arrow B, and

Fig. 4 is a sectional view, the left hand half being taken on line 2—2 and the right hand half on line 3—3 of Fig. 1.

Referring to these drawings the numeral 1 designates a casing adapted to be mounted for instance upon the chassis of a motor vehicle. This casing is divided substantially centrally by partitions or walls 2 so as to form two cylindrical chambers 3 and 4, in one of which 3 a variable stroke pump P is located and in the other of which 4 a motor M—which may conveniently though not essentially be of similar form to the pump—is arranged. The partition 2 consists of a circular disk formed upon the motor side with an eccentric boss 17 and this boss serves to support the ends of the shafts 6 and 14. Upon its other side the partition

2 is cut away centrally to accommodate the flange 9 and openings 2^a may be provided in the partition to permit free circulation of any working fluid which leaks past the pistons into the center of the apparatus. The inner walls of the cylinder bodies of the pump and motor rotate in contact with the partition 2. The variable stroke pump P consists in general of a rotating cylinder body 11 whose cylinders are open at their outer ends. Pistons 100 reciprocate in the cylinders, partition members 104 being provided in the casing to separate the suction side from the pressure side. Centrally of the casing 1, I provide a cylindrical member 106 which can conveniently be formed integral with one of the circular side walls 77 of the casing as shown. Upon this central cylindrical member 106 an inner eccentric sheave 7 is mounted and upon this inner sheave a second or outer eccentric sheave 8 is mounted and by means of internal teeth 110 in a rim or flange 111 of the outer sheave 8 and external teeth 112 on an extension 113 of the inner sheave 7 the two sheaves are geared together by a pinion 21 so that the pinion gearing with both the sheaves can be utilized to insure synchronous movement between the two sheaves. By this means the degree of eccentricity of the strap or ring 115 mounted upon the outer sheave 8 to the central axis of the machine can be varied at will. The teeth on the eccentric sheaves are so arranged that they are concentric with the axis of the machine. This strap or ring 115 is mounted upon a roller bearing 116 surrounding the outer sheave. The strap or ring 115 is provided in the construction shown on the drawing with flanges such as 120 to which connecting rods or links 121 are connected, the outer ends of these rods or links being connected to the pistons 100 with which the radial cylinders 103 are fitted. These flanges 120 on the strap aforesaid not only serve to enable these connecting rods to be attached but they also serve as clutch members so that projecting pins or the like 123 associated with the rotatable cylinder body or rotor 11 by means of engagement with radial slots 150 formed therein engage these flanges 120 on the strap or ring 115 and thus definitely drive it as the cylinder body rotates. This strap

may however be driven in other ways so long as some means is provided for causing the movement of the cylinder body or rotor of the machine to be transmitted to the 5 ring or strap 115 whatever the degree of eccentricity of the latter. In the form of machine shown in the drawings the rotor is coupled by means of studs to a driving shaft or spindle but any suitable means 10 may be provided for driving the rotor.

In order to enable the throw of the eccentric to be varied at will so as to vary the actual stroke of the piston 100 the pinion 21 gearing the two eccentric sheaves 7 15 and 8 is connected to or formed integral with a spindle 136 having a rapid thread—such as is used in an Archimedean drill—and this spindle passes through a member 19 slidable on an extension 138 of the central cylindrical member 106 upon which the eccentric sheaves 7 and 8 are mounted and it will be readily understood that if suitable means are provided for moving this slidable member 19 the pinion 21 will be 20 rotated and the throw thus adjusted. This form of operating the pinion is advantageous when the whole casing is revolved as would occur when the pump is employed as part of a transmission system, but where 25 the casing is always stationary as in a pump, any form of device for rotating the pinion may be adopted. In Figs. 1 and 4 it will be noted the strap or ring 115 is shown at its position of maximum eccentricity.

The motor M may be of any desirable form. In the example illustrated the motor is however of precisely the same form as the pump except that no provision is made 40 for varying the stroke of the pistons, an eccentric of fixed throw designated by the number 17 being provided. Axially of the casing and upon the pump side, I provide a hollow cylindrical member 106 which acts 45 as a bearing or support for a solid shaft or driving spindle 6, and also serves to support eccentrics 7 and 8, by means of which the stroke of the pump is varied and controlled as before described. The inner end 50 of the central shaft or driving spindle 6 is flanged as at 9 and by means of bolts 10 connection is made to the rotatable cylinder body or rotor 11 of the pump. The body 11 is indicated both in Fig. 1 and in Fig. 55 4, and is made in a ring-like form, but having radial apertures therein forming cylinders for the pump pistons 100. Member 11 is mounted within the outer casing 22. Upon the motor side of the apparatus 60 a bearing or support 12 furnished with a bush 13 in alinement with the bearing 106 supporting the driving shaft 6 is provided to support the spindle or shaft 14 to be driven and this driven spindle or shaft 14 65 at its inner end is adjacent the end of the

driving shaft 6. The driven shaft 14 aforesaid is by means of a flange 15 connected to the rotating member 16 of the motor M. The rotating member 16 of the motor is similar to the member 11 of the pump in 70 form and also is mounted within the outer casing ring 22 but is axially displaced from member 11. The outer surface of the bearing 12 supporting the driven spindle 14 is formed as an eccentric boss 17 which determines the stroke of the motor which it will be noticed need not be—and in this construction is not—variable. It will be understood that in operation the pump and motor are filled with working fluid, oil for 80 instance,—a suitable plug may be provided to enable the initial filling operation to be conveniently performed—and the liquid under pressure is delivered from the pump P to the motor M and operates to drive it and 85 the driven spindle 14 attached to it, and the speed of rotation of this driven spindle 14 is dependent upon the stroke of the pump which is dependent upon the throw of the compound eccentrics 7, 8. It will be 90 understood that liquid from the pump P is delivered through one of the ports 104^a to the cylinders of the motor, and operates upon the pistons so that the rotor of the motor which is attached to the spindle 14, 95 is driven around, carrying the pistons with it, and the reciprocation of the pistons returns the liquid to the suction side of the pump through the other of the ports 104^a, there being continuous circulation of the 100 liquid from the pump to the motor and from the motor body again to the pump. The direction of rotation will be dependent upon which side of the primary axis of the machine the eccentric is arranged. For 105 moving the slidable member 19 to vary the stroke of the pistons I provide a foot or hand lever connected with the collar 18 of the sliding member 19 which operates the stroke controlling spindle 20 to rotate the 110 pinion 21 gearing with eccentrics 7 and 8. Similarly I propose to provide foot or hand levers suitably located as part of the gear for operating the brakes which preferably take the form of contracting bands 115 co-operating with brake paths 122 formed upon or attached to the periphery of the casing 1. The casing as a whole is preferably mounted in plumber blocks and ball bearings 23 so that at top speed the whole casing can be allowed to rotate as a solid mass with no circulation of fluid and the driven shaft 14 will rotate at engine speed with 120 very high efficiency. Means may be provided for holding the casing stationary 125 when the driven shaft or spindle 14 will be rotated by the motor M which will as aforesaid be driven by the liquid under pressure delivered from the pump P. It will be understood that the same working fluid will 130

be circulated over and over again and provision may if necessary, be provided for compensating for any slight leakage which might occur from time to time.

5 For convenience the motor hereinbefore described and illustrated is similar in construction to the pump but I wish it to be understood that I do not confine myself to this particular type of motor since various 10 forms of motor may be employed but the motor—whatever form it may take—is preferably of the same cubic capacity as the pump.

What I claim and desire to secure by Letters Patent is:

1. A rotary transmission gear comprising in combination a pump structure having suction and delivery chambers, radially disposed partitions between said chambers, a 20 rotor rotating within the casing in contact with said partition, said rotor having radial cylinders therein open at their outer ends in communication with the suction and delivery chambers of the casing, pistons 25 reciprocating in the said cylinders and closing the inner ends of said cylinders, a rotatable ring or strap mounted eccentrically relative to the rotor body, an eccentric stationary relative to the strap or ring and 30 rotor body, said eccentric being located within said strap or ring, connections between the inner ends of the pistons and the eccentric strap or ring, means for insuring the rotation of the eccentric ring in com-

pany with the rotor, and a hydraulic motor 35 mounted in the same casing as the pump structure but separated from it by a dividing diaphragm through which the liquid delivered by the pump circulates.

2. A rotary transmission gear comprising 40 in combination a pump structure having suction and delivery chambers, radially disposed partitions separating said chambers, a rotor rotating within the casing in contact with said radially disposed partition, said 45 rotor having radial cylinders therein open at their outer ends and in communication with the suction and delivery chambers of the casing, pistons reciprocating in the cylinders and closing the inner ends of said cylinders, a rotatable strap or ring mounted eccentrically relative to the rotor body, connections between the inner ends of the piston and the eccentric strap or ring, a stationary eccentric located within said strap or ring 50 and disconnected therefrom, means for varying the eccentricity of the eccentric, and a hydraulic motor mounted in the same casing as the pump structure but separated 55 from it by a dividing diaphragm through which motor the liquid delivered by the pump circulates.

In testimony whereof I affix my signature in presence of two witnesses.

WILLIAM JOHN VINCENT.
